[57] CLAIM

The ornamental design for a self-stick removable note holder, as shown and described.

DESCRIPTION

FIG. 1 is a perspective view of the self-stick removable note holder in accordance with my new design;

FIG. 2 is a top plan view thereof;

FIG. 3 is a bottom plan view thereof;

FIG. 4 is a right side elevational view thereof (the left side elevational view is identical to the right side elevational view); and,

FIG. 5 is a front elevational view thereof (the rear elevational view is identical to the front elevational view).

FIG. 1

FIG. 2

FIG. 3

FIG. 4

FIG. 5
